FIG. 12.

FIG. 13.

INVENTOR:

GEORGE E. BISHOP

By

George W. Daywell
ATTORNEY

Patented July 3, 1923.

1,460,529

UNITED STATES PATENT OFFICE.

GEORGE E. BISHOP, OF CLEVELAND, OHIO.

AUTOMOBILE INCLOSURE.

Application filed January 20, 1922. Serial No. 530,574.

To all whom it may concern:

Be it known that I, GEORGE E. BISHOP, a citizen of the United States, resident of Cleveland, county of Cuyahoga, and State of Ohio, have invented new and useful Improvements in Automobile Inclosures (Case S), of which the following is a specification, the principle of the invention being herein explained and the best mode in 10 which I have contemplated applying that principle, so as to distinguish it from other inventions.

My invention relates to vehicle side inclosures and particularly to means of this 15 character adapted to be mounted upon the doors of an automobile so as to ride in and out with the latter as they are opened and shut. Particularly, the invention relates to improved means in such inclosures which 20 allow for the turning of a supporting rod relative to a frame upon which the fabric is carried, when the inclosure is not mounted for service, whereby the inclosure can be stored in a fairly flat condition. Also, the 25 inclosure frame and fabric can swing, relative to the rod and door, as the latter is opened and shut, so as to relieve the inclosure of strains to which it would otherwise be subjected.

30 The annexed drawings and the following description set forth in detail certain means embodying my invention, the disclosed means, however, constituting but a few of the various mechanical forms in which the 35 principles of the invention may be employed.

In said annexed drawings:

Figure 1 represents a side elevation of my 40 improved inclosure of the non-foldable type;

Figure 2 represents a transverse vertical section, upon an enlarged scale, taken in the plane indicated by the line II—II, Figure 1;

Figure 3 represents a transverse vertical section, also upon an enlarged scale, taken in the plane indicated by the line III—III, 45 Figure 1;

Figure 4 represents a fragmentary elevation, upon an enlarged scale, of my improved means providing for the turning of the supporting rod, when the inclosure is not mounted for service;

Figure 5 represents a fragmentary horizontal longitudinal section taken in the 50 plane indicated by the line V—V, Figure 4;

Figure 6 represents a fragmentary eleva-

tion, showing a modified form of supporting rod and modified means for connecting the same to the supporting frame;

Figure 7 represents a vertical transverse section, upon an enlarged scale, taken in the plane indicated by the line VII—VII, Figure 6;

Figure 8 represents a fragmentary side elevation, showing a second modified form 65 of supporting rod which can be not only turned but also rolled or folded in the curtain for storage, the inclosure herein shown being of a type allowing for rolling or folding.

Figure 9 represents a fragmentary side elevation, upon an enlarged scale, of the 70 supporting rod shown in Figure 8;

Figure 10 represents a side elevation of a third modified form of supporting rod;

Figure 11 represents a fragmentary elevation taken from the plane indicated by the line XI—XI, Figure 10;

Figure 12 represents a side elevation of my improved inclosure showing a modified 80 form of non-foldable frame for strengthening the curtain fabric; and

Figure 13 represents, upon an enlarged scale, a horizontal longitudinal section taken in the plane indicated by the line XIII—XIII, Figure 12.

Referring to the annexed drawings and particularly to Figures 1 to 7, in which the parts are indicated by the same respective ordinals in the several views, I indicate 90 suitable curtain fabric by the ordinal 1, in which is mounted a suitable transparency 2 disposed in the heading above the automobile door 36. When the inclosure is de-

signed for use also laterally of said door 95 heading, the fabric extension is provided with the transparency 3. The inclosure is designed, as the door 36 is opened and shut, to ride on the door, breaking between the transparencies 2 and 3 (in the type shown in Figure 1) in the plane containing the 100 vertical projection of the door hinges. Suitable strengthening means for holding the curtain fabric 1 taut are provided by means of a flat rod member 4 disposed near the upper edge of the fabric and preferably incorporated within the latter and extending from a point adjacent the opening edge 1' of the fabric 1 rearwardly to a point adjacent the line of breakage of the inclosure 105 and a metal strengthening member disposed near the bottom edge of the fabric 1, the

same being preferably a thin sheet metal plate 5 extending longitudinally from a point adjacent the opening edge 1' of the inclosure to a point adjacent the line of 5 breakage, and extending vertically from the bottom edge of the fabric 1 to a line somewhat above the top edge of the automobile door 36. Where the inclosure is designed for use also laterally of the door heading, a 10 rear bottom edge sheet metal strengthening member 6 is disposed adjacently below the transparency 3. To complete a U-frame strengthening member (Figure 1) I provide a vertical front metal member, preferably a 15 flat rod 7, pivotally secured at its respective bottom and upper ends 8 and 9 to the bottom sheet metal strengthening member 5, and the upper rod 4. In the type shown in Figure 1, I provide a second vertical rod 7 20 pivotally secured at its bottom end to the sheet metal member 6 and at its top to the rear of a metal reinforcing valance member 13 which will later be fully described. I have shown and described valances of this 25 general type in previous patent applications and have particularly patented the same in U. S. Letters Patent, No. 1,244,692. To the type of valance thus patented I have, in the showing made in this application, added 30 metal reinforcements. I shall now describe the valance as a whole including these reinforcements. The fabric portion of the valance consists of sections 14 and 15, rear section 14 being riveted to the portion of the 35 inclosure laterally of the door heading, as indicated by the ordinals 11, and capable of being suitably secured to the canopy top, as indicated by the ordinals 12. The valance is not rigidly secured to the inclosure 40 portion above the door heading, and in fact, is only a bumper for said inclosure portion as the door 36 closes, Figure 7. The forward valance portion 15 is capable of being secured to the canopy top, as indicated by 45 the ordinal 16. Within the fabric valance sections 14 and 15, I incorporate a reinforcing strengthening member, preferably the sheet metal member 13.

The inclosure proper above described is 50 designed to be mounted upon the automobile door 36 and to this end I provide a cylindrical supporting rod 18 having preferably, and if the desired lapping of the inclosure, as well as the automobile construction so requires, an offset lower end 19 provided with a plane extreme end portion 20 adapted to engage a co-operating socket secured to the door 36 or mounted therein, to prevent the turning of the rod 18 upon or in the door 36. Pivotally secured to the fabric 1, and 55 preferably to the longitudinal strengthening member 4 also, is an upper supporting rod tip section 21, as plainly shown in Figure 1. This tip 21 is formed with a tubular 60 recess 22 adapted to receive the extreme 65

upper end portion of the cylindrical rod section 18. In order that the rod 18 may be suitably movably held to the inclosure proper, I provide the improved securing means now to be described. These means comprise a cylindrical metal clip 23 secured adjacent the lower opening edge of the fabric 1 and preferably also riveted to the sheet metal strengthening member 5, the clip having a recess 25 adapted closely to receive the supporting rod section 18. The clip section forming the wall of this recess 25 is formed with a horizontal longitudinal slot 24 which is intersected by a pin 26 secured to the supporting rod section 18. This construction provides economical and efficient means for holding the bottom of the inclosure closely to the supporting rod and also for turning the rod, when the inclosure is removed from the automobile door, so that the rod can be stored in a flat condition. The rod section 18, of course, turns also in the swinging tip 21. It is evident also that the inclosure proper, when assembled, can turn upon the rod 18 by means of the pivotal connection of said rod 18 with the rod tip 21 and by reason of the fact that the clip 23 is free to move about the rod 18, the slot portion 24 travelling by the pin 26. This relieves the inclosure of many strains to which it would be subjected, when it rides in and out with the door 36, if the rod 18 were rigidly secured to the inclosure proper. The pivotal connection at the points 8 and 9 between the upper and lower metal strengthening members 4 and 5 and the vertically-disposed strengthening member 7, is obtained by punching a hole through one of said members and punching the other member so that the material thereof is laterally 95 extended into a broken generally conical protuberance which is inserted through the hole of the first-mentioned member and then the outer edge of the protuberance upset to produce a secure connection which, however, allows for the relative pivotal movement of the two members. This sort of a connection permits the throwing up of the rear of the inclosure into proper position by reason of the relative pivotal movement of the parts of the supporting frame. It will be noted that in this construction the whole inclosure is stiffened except in the line of the door hinges. In the type shown 100 in Figure 1, the pivotal connections between the members 6 and 13 and the vertical member 7 are obtained in the same manner, and this type of connection is particularly shown, described and claimed in my pending application, Serial No. 398,138.

In the form of inclosure illustrated in Figures 6 and 7, the supporting rod tip section 21 is formed with a vertically-disposed open-ended recess 27 in its upper end which is adapted to receive the longitudinal 120 125 130

strengthening member 4. A modified and permanent connection between the rod sections 18 and 21, which also allows for their relative pivotal movement, is also disclosed 5 in that the upper journal end of the rod section 18 is of reduced cross-sectional area and is formed with an annular peripheral recess 30 into which extends an inwardly projecting bead or lug 28 formed in the 10 lower tubular section 22 of the rod tip 21.

In the form of device illustrated in Figures 8 and 9 modified means for separably holding together the tip 21' and the main supporting rod section 18 is shown. These 15 modified means consist in a sleeve 31 formed of end sections of varying diameters and an intermediate shoulder 31' which normally rests upon the top of the rod section 18 which is of larger cross-sectional area than 20 the solid tip 21'. The adjacent ends of the tip 21' and the rod 18 abut in the assembled condition of the inclosure and the shoulder 31' in the assembled condition of the inclosure lies substantially in the same 25 plane as these abutting ends of the rod 18 and the tip 21'. The respective ends of the sleeve 31 closely and slidably receive the abutting ends of the rod 18 and the tip 21'.

Also the form of supporting frame shown 30 is a modified type in that the vertical side member 7 is omitted, so that the frame is collapsible. Now, when it is desired to collapse the supporting rod, the section 18 thereof is relieved from the sleeve 31 simply 35 by raising said sleeve into the position shown in dotted lines in Figure 9, when said rod section 18 can be turned down into any desired position as illustrated by the dotted line position thereof in Figure 8. When 40 this type of inclosure is stored, it is rolled or folded and the supporting rod is stored in sections therein. It is evident that the tip 21' can turn relatively to the rod 18 so that in this form of inclosure the same provision 45 is made as in the previously described forms for relieving the inclosure of strains during the opening and closing of the door 36. The sleeve 31 and its related elements, for use in a structure of this type, is particularly patented to me in U. S. Patent No. 50 1,323,439.

In the form of device illustrated in Figures 10 and 11, I have dispensed with the tip 21 and therefore with the means for 55 allowing a relative movement, when assembled, between the top of the inclosure and the supporting rod, and have utilized simply the form of rod which is disclosed in Figure 6, this form of rod in Figures 10 and 11 being indicated by the ordinal 32 and extending upwardly to the longitudinal 60 strengthening member 4 which it engages through the medium of the open-ended recess 27. In this form of rod the bottom supporting end 20' may be circular in cross-

section, inasmuch as the rod cannot turn in the door socket due to the non-turning connection, at the top of the rod, with the strengthening member 4.

In the form of inclosure shown in Figures 12 and 13 which is provided with a two-socket attachment to the door 36 through the medium of a pair of front and rear supporting rods 18, I have made the peripheral strengthening frame of one continuous piece 70 of sheet metal 33 extending from the transparency 2 to the edge of the fabric 1. I also show a horizontally disposed wood strip 34 disposed parallel adjacently above the top edge of the door 36 and to which is attached 75 to the sheet metal 33 by means of clinched nails 35. To this wood strip 33 is attached the usual inclosure flap which maintains the proper horizontal relation of 80 the inclosure section.

What I claim is:

1. An automobile side inclosure adapted to be mounted upon the automobile door, comprising suitable curtain fabric; metallic strengthening means for said fabric; means for mounting the inclosure upon the door, said mounting means being connected to the fabric adjacent the upper edge of the latter; and mounting-receiving and securing means secured to the fabric adjacent the lower edge of the latter, the mounting being turnable in said last-mentioned means. 95

2. An automobile side inclosure adapted to be mounted upon the automobile door, comprising suitable curtain fabric; metallic strengthening means for said fabric; means for mounting the inclosure upon the door, said mounting means being connected to the fabric adjacent the upper edge of the latter but movable relatively thereto; and mounting-receiving and securing means secured to the fabric adjacent the lower edge of the latter and having a movement about the axis of the mounting. 100

3. An automobile side inclosure adapted to be mounted upon the automobile door, comprising suitable curtain fabric; a metallic U-frame incorporated therewith comprising upper and lower metal members and a lateral intermediate metal member 115 connecting said upper and lower members; means for mounting the inclosure upon the door, said mounting means being connected to the fabric adjacent the upper edge of the latter but movable relatively thereto; and mounting-receiving and securing means secured to the fabric adjacent the lower edge 120 of the latter and having a movement about the axis of the mounting.

4. An automobile side inclosure adapted to be mounted upon the automobile door, comprising suitable curtain fabric; a metallic U-frame incorporated therewith comprising upper and lower metal members and a lateral intermediate metal member piv- 125 130

- totally connected to said upper and lower members; means for mounting the inclosure upon the door, said mounting means being connected to the fabric adjacent the upper edge of the latter but movable relatively thereto; and mounting-receiving and securing means secured to the fabric adjacent the lower edge of the latter and having a movement about the axis of the mounting.
10. 5. An automobile side inclosure adapted to be mounted upon the automobile door, comprising suitable curtain fabric; a metallic frame incorporated therewith comprising upper and lower metal members and lateral intermediate metal members connecting said upper and lower members; means for mounting the inclosure upon the door; mounting-receiving means secured to the fabric, movable relatively thereto and receiving one end of the mounting; and other mounting-receiving means secured to the fabric and receiving the other end of the mounting, both of said receiving means having a movement about the axis of the mounting.
15. 6. An automobile side inclosure adapted to be mounted upon the automobile door, comprising suitable curtain fabric; a metallic frame incorporated therewith comprising upper and lower metal members and lateral intermediate metal members connecting said upper and lower members; a cylindrical rod having a supporting end non-circular in cross-section; a member pivoted to the upper metal member and having a socket rotatably receiving the upper rod end; and a member secured to the lower metal member, said last-named member receiving and guiding the supporting rod but having a movement about the axis of the latter.
20. 7. An automobile side inclosure adapted to be mounted upon the automobile door, comprising suitable curtain fabric; a metallic frame incorporated therewith comprising upper and lower metal members and lateral intermediate metal members connecting said upper and lower members; a cylindrical rod having a supporting end non-circular in cross-section; a member pivoted to the upper metal member and having a socket rotatably receiving the upper rod end; and a member secured to the lower metal member, said last-named member receiving and guiding the supporting rod but having a movement about the axis of the latter.
25. 8. An automobile side inclosure adapted to be mounted upon the automobile door, comprising suitable curtain fabric; a metallic frame incorporated therewith comprising upper and lower metal members and lateral intermediate metal members pivotally connected to said upper and lower members; means for mounting the inclosure upon the door, said mounting means being connected to the fabric; and mounting-receiving means secured to the fabric, the latter means securing said mounting but having a movement about the axis of the latter.
30. 9. An automobile side inclosure adapted to be mounted upon the automobile door, comprising suitable curtain fabric; a metallic U-frame incorporated therewith comprising upper and lower metal members and a lateral intermediate metal member connecting said upper and lower members; a cylindrical rod having a supporting end non-circular in cross-section; a member pivoted to the upper metal member and having a socket rotatably receiving the upper rod end; and a cylindrical clip secured to lower metal member and having a transverse slot, the supporting rod being received and guided by said clip and being formed with a pin intersecting said slot.
35. 10. An automobile side inclosure adapted to be mounted upon the automobile door, comprising an upper flat rod, a lower sheet metal member and a lateral intermediate flat rod connecting said upper and lower members; a cylindrical rod having a supporting end non-circular in cross-section; a member pivoted to the upper rod and having a socket rotatably receiving the upper rod end; and a cylindrical clip secured to the lower sheet metal member and having a transverse slot, the supporting rod being received and guided by said clip and being formed with a pin intersecting said slot.
40. Signed by me this 9th day of January, 1922.
45. GEORGE E. BISHOP.
